(57) **CLAIM**

We claim the ornamental design of a coil assembly for solenoid valve, as shown and described.

DESCRIPTION

FIG. 1 is a front elevation view of a coil assembly for a solenoid valve showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is front, left and top perspective view thereof;

FIG. 8 is a rear, left and top perspective view thereof;

FIG. 9 is a front, left and bottom perspective view thereof;

FIG. 10 is a rear, left and bottom perspective view thereof; and,

FIG. 11 is a front, left and bottom perspective view thereof, shown in condition of use.

The broken lines shown in FIG. 11 are for the purpose of illustrating environment which form no part of the claimed design.

The coil assembly for a solenoid valve is shown with a symbolic break in its length. The appearance of any portion of the article between the break lines forms no part of the claimed design.
